COMBINED TEETER-TOTTER AND ROUNABOUT

Walter E. Froehlich, 220 Oak Ave.,
Galt, Calif. 95632

Filed Apr. 16, 1969, Ser. No. 16,762

Term of patent 14 years

Int. Cl. D21—03

U.S. Cl. D34—5

FIG. 1

FIG. 2

FIG. 3

FIGURE 1 is a top plan view of a combined teeter-totter and roundabout showing my new design;

FIGURE 2 is a side elevational view, the opposite side being substantially similar in appearance;

FIGURE 3 is an end elevational view, the opposite end being substantially similar in appearance; and

FIGURE 4 is a sectional view to an enlarged scale, the plane of the section being indicated by the line 4—4 in FIGURE 2.

I claim:

The ornamental design for a combined teeter-totter and roundabout, as shown.
